UNITED STATES PATENT OFFICE.

MARTIN R. FORY, OF NEW YORK, N. Y., AND WILLIAM L. HEGEMAN, OF JERSEY CITY, N. J., ASSIGNORS TO MARTIN R. FORY, OF NEW YORK, N. Y.

WATER-CLOSET.

SPECIFICATION forming part of Letters Patent No. 229,112, dated June 22, 1880.

Application filed August 22, 1879.

To all whom it may concern:

Be it known that we, MARTIN R. FORY, of New York city, New York, and WILLIAM L. HEGEMAN, of Jersey City, New Jersey, have 5 invented new and useful Improvements in Water-Closets, of which the following is a specification.

Our invention relates to improvements in valves and valve-operating devices for water-closets; and the object of our invention is to provide for the free escape of the contents of the basin, to effectually seal the outlet without the use of water, and to improve the devices for operating the valve. These objects 15 we attain in the manner which we will now proceed to describe, reference being had to the accompanying drawings, illustrating the application of our improvements to a portable water-closet.

20 In the drawings, Figure 1 is a sectional view of a portable water-closet with our improvements; Fig. 2, a plan view of the basin; and Fig. 3, a sectional plan on the line 1 2, Fig. 1.

A is a casing, to the upper edge of which is 25 adapted the seat *a* of the basin *B*, a tubular ring, *b*, of rubber, or other elastic ring, insuring a tight joint between the seat and casing.

In the seat *a*, and in a bracket, *d*, secured to one side of the basin, are formed bearings 30 for a rod, *D*, having at the upper end a handle, *e*, and at the lower end an arm, *f*, which carries a valve, *E*, adapted to the opening at the lower end of the basin *B*.

The rod *D* is so adapted to its bearings that 35 it can be moved up and down and turned laterally therein, a plate, *i*, however, adapted to a squared portion of the rod, serving to limit the turning movement by coming into contact with a shoulder, *m*, on the bracket *d*. (See Fig. 3.) 40 A spring, *n*, surrounding the rod *D* tends to elevate the same.

J is an elevated water-reservoir, from which a flexible tube, *j*, extends to the basin *B*, with which the said tube communicates through 45 the usual opening *k*. The passage of water from the reservoir into the tube *j* is determined by the operation of a valve, *p*, to which is connected a cord or chain, *s*, passing over a pulley, *t*, at the top of the reservoir, and hanging down 50 outside the same, the lower end of the pend-

ent cord being provided with a ring, *v*, or equivalent device, which is within convenient reach of the occupant of seat *a*.

The casing *A* contains a vessel, *M*, which is arranged immediately beneath the basin *B*, for 55 receiving the soil, &c., discharged from the latter.

The discharge-valve *E* has a body of wood or metal, covered with rubber or like elastic material, *w*, and beneath the covering, and at a 60 point where the valve comes into contact with its seat on the edge of the opening in the basin *D*, is arranged a ring, *x*, of elastic material.

When the water-closet is not in use the parts are in the position shown by full lines in 65 Fig. 1; but after the water-closet has been in use, and it is desired to discharge the contents from the basin, the rod *D* is first pushed down, as shown by dotted lines in Fig. 1, and then turned laterally, so as to swing the valve *E* 70 away from the opening of the basin, as shown by dotted lines in Fig. 2, when the contents of the basin and the water which is used for washing the same will be discharged into the vessel *M*, after which the rod *D* is so operated as 75 to restore the valve *E* to its original position, where it effectually seals the lower end of the basin and prevents the escape of foul vapors from the interior of the casing *B*.

Being independent of a water-seal in making a tight joint, our improved water-closet can be used in the coldest weather without danger of being rendered inoperative by the freezing of the water in the seal.

Instead of first depressing and then turning the rod *D* by hand, the rod might be provided with a scroll-cam so arranged in respect to a stationary pin that the downward movement of the rod would be simultaneous with the turning of the same.

The basin and its attachments may be applied to the seat of an ordinary privy or may be used in connection with a fixed water-closet.

We do not desire to claim, broadly, a valve carried by a rod which is adapted to receive a 95 longitudinal and vibrating motion to apply the valve to or remove it from its seat; but

We claim as our invention—

1. The combination of the basin having a valve-seat with a valve, *E*, and rod *D*, passing 100

through the seat and carrying the valve at its lower end, and provided with a handle at the upper end, as set forth.

2. The combination of the basin, the valve 5 E, the rod D, and spring n, as set forth.

3. The combination of the rod D, the stop-
plate i, and the bracket d, having a shoulder,
m, as described.

4. The valve having the elastic covering w
10 and internal elastic ring, x, as set forth.

In testimony whereof we have signed our names to this specification in the presence of two subscribing witnesses.

MARTIN RUDOLPH FORY.
WILLIAM L. HEGEMAN.
